UNITED STATES PATENT OFFICE.

CHARLES M. DOLAND, OF SPOKANE, WASHINGTON.

THERMOMETER-CASING.

1,169,137.

Specification of Letters Patent. Patented Jan. 25, 1916.

Application filed June 9, 1914. Serial No. 644,009.

To all whom it may concern:

Be it known that I, CHARLES M. DOLAND, a citizen of the United States, residing at Spokane, in the county of Spokane and State of Washington, have invented certain new and useful Improvements in Thermometer-Casings, of which the following is a specification.

This invention relates to improvements in thermometer casings.

Practising physicians in making a number of calls are now required to carry with them a number of thermometers by reason of the fact that it is necessary to thoroughly disinfect a thermometer after the temperature of a patient has been taken.

It is one of the objects of this invention to provide a casing structure wherein the thermometer may be projected and withdrawn and thoroughly disinfected after it has once been used, so that it can be again used for the next patient, thereby avoiding the necessity of carrying a number of thermometers.

In the most preferred embodiment of the invention the same includes an outer casing in which a wick-like thermometer container is adapted to be inserted after being impregnated with a disinfectant such for instance as formaldehyde. The casing itself may in addition be supplied with a disinfectant so that the wick container may be maintained in a saturated condition by capillary attraction. It is contemplated that by merely inserting and withdrawing the thermometer into and from the container, that the surface of the thermometer will be thoroughly disinfected.

The invention also relates to an improved and novel form of container which in the most preferred construction has a cross section less than the cross section of the thermometer so that the latter will not only expand the container but will serve to compress the texture of the container against the casing in such a manner as to cause a seeping discharge of the liquid from the texture of the container onto the peripheral surface of the thermometer.

Other features of novelty will be more fully described in connection with the accompanying drawing and will be more particularly pointed out in and by the appended claims.

In the drawing:—Figure 1, is a view in elevation of my improved container de-

tached from the casing. Fig. 2, is a sectional view of my improved casing with the container and thermometer therein. Fig. 3, is an enlarged vertical sectional view of the mouth or intake end of the container.

Like characters of reference designate similar parts throughout the different figures of the drawing.

As illustrated, 1 designates an imperforate casing which may be formed of any desired material and which is preferably longer than the thermometer to be inserted therein. Throughout the major portion of its length, the casing 1 is of uniform cross section but near its open end the casing is enlarged, as indicated at 2, and with a view of forming a shoulder 3, the purpose of which will presently appear. I may, if desired, interiorly thread the open end 2, as clearly shown in Fig. 2 of the drawing. A cap 4 may be provided having a cross section complementary with respect to the cross section of the casing 1, and I have shown the cap provided with an annular bead 5 adapted to abut against the open end 2 so as to limit projection of the end 6 of the cap into the open end 2 of the casing 1. In the present construction, I exteriorly thread the end 6 of the cap for engagement with the interior threads of the end 2 of the casing and I reduce the length of the end 6 of the cap so that when the latter is turned into a full closing position, the margin of the end 6 of the cap will not extend to the shoulder 3, a space being provided the function of which will presently appear. In the interior of the cap 4 I dispose a wadding 7, for engagement with the end of the thermometer 8.

A container 9 of wick-like material is provided for insertion into the casing 1 and the normal cross section of the container 9 will be considerably reduced with respect to the interior cross section of the casing 1 to permit of readily inserting the container into the casing. The container 9 is an open ended tubular body and I provide at the intake end of the container a ferrule 10 which is of U-shaped cross section with the U-flanges 11 folded over the margin of the intake end of the tube 9. The diameter of the ferrule 10 is greater than the normal diameter of the tube container 9 so as to spread or flare the intake end of the container to hold the same open for insertion of the thermometer 8, and for the further rea-

son that by increasing the diameter of the ferrule with respect to the container, the outer U-flange 11 will seat the shoulder 3 of the casing 1. It is also a feature of the invention that the ferrule is increased with respect to the diameter of the thermometer to be used so that the interior U-flange 11 will not engage the surface of the thermometer and scratch the same.

10 It is a further feature of my invention to not only reduce the tubular container 9 in cross section with respect to the cross section of the casing 1, but also as regards the cross section of the thermometer 8, in such a manner that when the thermometer 8 is inserted into the container 9, as shown in Fig. 2, the container will not only be expanded from its normal size but will be compressed against the wall of the casing 1 so as to cause seeping discharge of the liquid or disinfectant with which the container has been impregnated, onto the surface of the thermometer so as to disinfect the latter.

In order to accommodate the container for thermometers of different lengths, I provide means for adjustably closing the normally closed end of the container so as to limit projection of the thermometer therein and thereby always insure a sufficient length of projection of the base end of the thermometer 12, from the casing 1, so that the thermometer can be readily grasped and be withdrawn from the case 1.

As illustrated, I close the lower end of the container 9 by means of thread or other binding material 13 which may be disposed about the tubular container 9 at such a distance as to prevent the reduced end 14 of the thermometer 8 from passing downwardly into the container 9 beyond a predetermined extent.

In use, the container may be withdrawn from the casing and dipped into a suitable disinfectant so as to saturate the container, and then the latter will be inserted into the casing 1. Ordinarily, by inserting and then withdrawing the thermometer into and from the container, the thermometer will be thoroughly disinfected. If desired, however, the thermometer can be inserted and permitted to remain in the container for prolonged contact with the disinfectant with which the container is saturated. The casing 1 may, if desired, contain a quantity of disinfectant liquid in the space afforded at 15, and the gathered and closed end 16 acts as a collecting reservoir to promote capillary attraction upwardly in the container, provides for a more effective capillary attraction and reduction of the container and also serves to provide a space in which liquid can be disposed without unduly lengthening or enlarging the casing 1.

By suitably shortening the end 6 of the cap 4, I provide sufficient intervening space

to accommodate the ferrule 10 so that the latter will be rigidly and securely clamped in place upon the shoulder 3 when the cap 4 is turned into position.

By reason of the fact that the container 9 substantially completely envelops the thermometer 8, ample protection is afforded against breakage of the latter and I am also enabled to use a relatively cheaply constructed casing 1, the container being economically discarded when desired or when they have become unfit for further use.

It is believed that the advantages and utility of my invention will be clearly understood from the foregoing description, and while I have herein shown and described one specific form of my invention, I do not wish to be limited thereto except for such limitations as the claims may import.

I claim:—

1. In a thermometer structure, a casing, a wick-like thermometer container in said casing having originally open ends, means for closing one end at different lengthwise points of the container to vary the containing length thereof, and ferrule means secured to the remaining end of the container and proportioned to originally hold such remaining end in a spread or open position at a cross section exceeding the normal cross section of the container, substantially as described.

2. In a thermometer structure, a casing having an open end, and a wick-like thermometer container of originally reduced cross section with respect to the interior cross section of said casing, and a ferrule secured to the open end of said casing and having an interior cross section exceeding the cross section of the thermometer to be used and connected with the container to flare the mouth thereof outwardly from the normal cross section of the container, substantially as described.

3. In a thermometer structure, a casing having an open enlarged end and provided with an interior shoulder disposed inwardly with respect to the marginal edge of said open end and said open end being threaded for a portion of its length toward said shoulder, a wick-like container of originally reduced cross section with respect to the interior cross section of the casing, a ferrule adapted to seat on the shoulder of the open end of said casing and having an interior cross section exceeding the cross section of the thermometer to be used and connected with the container to flare the mouth thereof outwardly, and a cap having interior threaded connection with the open end of said casing and extending downwardly therein for engagement with said ferrule to seat the same upon said shoulder, substantially as described.

4. In a thermometer structure, a casing

having an open end and of a length exceeding the length of the thermometer to be used, a fabric-like container of reduced length with respect to the thermometer to be used; said casing and container being provided with coacting portions for limiting insertion of the latter into the former to a predetermined position therein, and adjustable means for gathering and closing 10 the lower end of the container to neutralize the shock of and limit projection of thermometer therein and insure projection of a portion of the thermometer from the open

end of the casing when the thermometer is fully inserted into the container, said gathered end acting as a reservoir to collect and hold the disinfectant and promote capillary attraction upwardly in said container, substantially as described. 15

In testimony whereof I affix my signature 20 in presence of two witnesses.

CHARLES M. DOLAND.
